INFLATION ASPIRATOR LOCK

Robert J. Fraebel, Red Bank, N.J., assignor to The Garret Corporation, Los Angeles, Calif., a corporation of California

Filed July 18, 1960, Ser. No. 43,612

6 Claims. (Cl. 230—95)

This invention relates generally to apparatus for inflating devices such as life rafts, escape slides, shelters and other structures which are designed to be filled with air or gases under relatively low pressure. In view of the fact that life rafts and escape slides are used in the evacuation of abandoned craft, the inflating apparatus for these devices must not only be able to inflate the device rapidly, but must also be capable of maintaining the preselected pressure within the inflated device for long periods of time. Leakage of air or gas out of the inflated device therefore must be held to a minimum.

Container-inflating apparatus of the type shown in the Crawford et al. Patent, No. 2,772,829, is now used to inflate life rafts, escape slides, and other emergency devices. The apparatus disclosed in the above noted patent includes a jet pump or aspirator which has a body of tubular configuration, a nozzle for directing a jet-like stream of air or gas from a suitable source into or through the body, and check valve means movable between an open position providing for the entrance of atmospheric air into the container and a closed position for preventing the escape of air from the container.

While the aspirator in the above-noted patent will quickly inflate a container, under some circumstances there is danger that after the container is inflated the check valve means may inadvertently or accidentally be opened and permit the escape of air or gas from the container. Accordingly, it is an object of the present invention to provide container-inflating apparatus of the type shown in the above Crawford et al. patent with means for locking the check valve means in the closed position.

It is a further object of the invention to provide container-inflating apparatus of the aforementioned type with means associated with the jet nozzle for locking the check valve means in the closed position.

It is a still further object of the invention to provide container-inflating apparatus of the aforementioned type having yieldable means urging the locking means into engagement with the check valve means, the fluid under pressure acting in opposition to the yieldable means to urge the locking means away from the check valve means and unlock it.

Other and further objects of the present invention will become apparent from the disclosures in the following detailed specification, appended claims, and accompanying drawing in which one form of the invention has been illustrated.

In the drawing:

FIGURE 1 is a view of an inflation aspirator of the type shown in the aforementioned Crawford et al. Patent No. 2,772,829, having a device for locking the check valve in the closed position;

FIGURE 2 is a detailed vertical sectional view taken on line 2—2 of FIGURE 1;

FIGURE 3 is a horizontal transverse sectional view taken on line 3—3 of FIGURE 2;

FIGURE 4 is an isometric view of the piston of the inflated apparatus.

Referring to the drawing there is shown inflation apparatus including a tank or bottle 11 connected to a conduit 12 and having a valve 13 for controlling flow of high pressure air or other fluid issuing from the tank to a regulator 14. The construction and operation of regulators suitable for this use are known in the art, an example be-

2

ing shown and described in the Crawford et al. U.S. Patent 2,935,084. The regulator 14 reduces the pressure of the fluid issuing from the tank 11 and maintains the air flowing from the regulator at a predetermined pressure. It should be noted, however, that the regulator 14 is not necessary to the functioning of the locking device disclosed herein and may be omitted.

A conduit 15 leads from the regulator 14 to a jet pump or aspirator, shown generally at 16, which is secured in 10 the inlet of a collapsible container, such as a fabric or plastic bag 17, a portion only of which has been illustrated in the drawing. The bag 17 may be a life raft, an escape slide, or other type of inflatable device.

The aspirator 16 is adapted to effect rapid inflation of 15 the bag 17 and includes a body 18 which, in the present instance, has an inlet end 20 of rectangular or square cross section which converges into an outlet portion 21 having a circular cross section. The inlet section 20 is provided with an external flange 22 which is secured 20 to a valve plate shown generally at 23. The valve plate 23 is also rectangular, to conform to the inlet section 20, and is provided with a peripheral flange 24. The flanges 22 and 24 are secured together by fastening means such as screws 25, the head of the screws securing a collar 25 26 to the aspirator and serving to unite the aspirator and the bag 17, the connection between the aspirator and bag being made airtight by clamping the bag between the collar and the valve plate.

A rubber or other flexible plate-like member 30 is secured between flange 22 of the body 20 and flange 24 of the valve plate 23 in airtight relationship with the body.

The member 30 has slots 38 and 39 formed therein to provide substantially rectangular check valve flaps 40 and 41, these flaps being joined with the member 30 along regions located at opposed sides of the inlet section of the body 18. This arrangement permits the valve flaps 40 and 41 to swing into the body without undue interference. The valve plate 23 is provided along the sides 40 of the openings formed therein with flanges 42 which engage the valve flaps 40 and 41 on two sides to prevent these elements from swinging outwardly under the influence of pressure within the body 18 or the bag 17. When the flap valves engage the flanges, an airtight joint 45 will be formed. The flaps may, if desired, be reinforced by moulding them about fabric or metallic sheeting 43 during the formation of the member 30. This reinforcement will prevent the flaps from flexing when pressure urges them against the flanges.

50 The valve plate 23, in the present illustration, has a rib 51 extending from opposite sides of the plate 23 to a cylinder 52 disposed centrally of the plate, the plate providing a rectangular opening constituting a continuation of the inlet portion of the body 18. The cylinder 52 is 55 provided with a fitting 53 threaded at one end to receive the conduit 15 and having a chamber 54 for receiving fluid from the regulator 14. A piston 55 disposed for longitudinal movement within the cylinder 52 is provided with a passage 56 for conducting air or fluid from the chamber 60 54 to a restricted nozzle 58 formed in a locking bar 60 secured on the other end of the piston in the manner hereinafter described. It will be noted that the nozzle 58 terminates at a point spaced inwardly from the flap valves. This arrangement prevents the high velocity air issuing from the nozzle from engaging the flaps and tending to swing them toward the open position.

65 The means provided for locking the valve flaps 40 and 41 in the closed position includes the locking bar 60 which is secured to the lower end of the piston 55 by a press fit 70 or other means well known in the art and extends outwardly from each side of the piston. A spring 62 disposed between a shoulder 63 formed on the piston 55 and

an opposing shoulder 64 formed on the inner surface of the cylinder 52 urges the piston in the upwardly direction and tends to move the bar 60 into engagement with the flaps 40 and 41. The piston 55 is provided with a helical groove 66 formed on its peripheral surface which is adapted to receive a matching key 67 extending radially inwardly from the inner surface of the cylinder 52, the key 67 and the groove 66 coact to rotate the piston about its longitudinal axis simultaneously as it moves axially within the cylinder.

Prior to initiating inflation of the container the force of the spring 62 acting through the piston 55 will urge the locking bar 60 into contact with the check valves 40 and 41 and the locking bar will assume the position shown in full in FIGURE 2, lying across the check valves and locking them in the closed position.

When it is desired to inflate the container, the valve 13 on the bottle 11 is opened to permit high pressure fluid to flow from the bottle through the regulator 14 to the chamber 54. The pressure of the fluid in chamber 54 acting on the piston 55 will overcome the force of the spring 62 and move the piston downwardly within the cylinder 52. As the piston moves downwardly the key 67 and the groove 66 coact to rotate the piston about its longitudinal axis so that the locking bar 60 rotates as it moves downwardly and moves from the position shown in full in FIGURE 2 to a position parallel with the contiguous inner edges of the valve flaps, as shown in phantom in FIGURES 2 and 3.

As the locking bar 60 moves to the unlocked position, the jet stream of air issuing from the orifice 58 mixes with the air in the body 18 and flows through the outlet portion 21 of the body into the bag 17. This flow of air reduces the pressure at the inlet end below the atmospheric pressure existing externally of the bag and the pressure of the atmospheric air acting on the outer surfaces of the flap valves 40 and 41 swings the valves inwardly toward an open position, permitting the atmospheric air to enter the bag and mix with the jet stream issuing from the nozzle.

When the pressure at the source is reduced and the velocity of the jet falls, the tendency of the air within the container to flow outwardly through the body will cause the check valves to close. Since the pressure of the air from the source will still be above that of the container, air will continue to flow from the nozzle and tend to increase the pressure within the container.

As the pressure of the fluid in the container approaches the pressure of the fluid in the inlet chamber 54 the force of the spring 62 acting on the piston 55 will move the piston in the upward direction and the locking bar 60 will be rotated to lie across the check valves 40 and 41, locking them in the closed position. When the storage pressure in the bottle is shut off the spring 62 will continue to urge the piston 55 in the upward direction and the locking bar will continue to hold the check valves in the closed position.

While the invention has been illustrated in one embodiment only, many minor changes may be made in the formation and arrangement of parts without departing from the spirit and scope of the invention as set forth in the following claims.

I claim:

1. In apparatus for inflating a container, an aspirator comprising a body having inlet and outlet ends, said body being formed for attachment to the container to be inflated; nozzle means projecting into said body at the inlet end thereof for directing a jet of fluid into said body, said nozzle means being arranged for communication with a source of fluid under pressure; check valve means mounted for swinging movement into said body at the inlet end thereof, said check valve means being adapted to swing inwardly in response to fluid flowing through said nozzle means into an open position providing for the entrance of ambient atmosphere into said container

and to swing outwardly in response to pressure of fluid in the container to a closed position preventing the escape of air from said container; and locking means including a member normally adapted to be urged into engagement with said check valve means to hold said check valve means in said closed position, said fluid under pressure acting on said locking means to move said member away from said check valve means to permit said check valve means to open to admit ambient atmosphere.

10 2. In apparatus for inflating a container, an aspirator comprising a body having inlet and outlet ends, said body being formed for attachment to the container to be inflated; nozzle means projecting into said body at the inlet end thereof, said nozzle means being formed for communication with a source of fluid under pressure; check valve means supported adjacent the wall of said body at the inlet end thereof, said check valve means being mounted for swinging movement into said body to open in response to fluid flowing through said nozzle means to admit ambient atmosphere; means for limiting outward swinging movement of said check valve means to prevent escape of air from said container when said container is inflated; and locking means normally including resilient means adapted to urge said locking means into engagement with said check valve means to maintain said check valve means in position to prevent escape of air from said container, said fluid under pressure acting on said locking means in opposition to said resilient means to urge said locking means away from said check valve means to permit said check valve means to swing into said body to open.

3. In apparatus for inflating a container, an aspirator comprising a body having inlet and outlet ends, said body being formed for attachment to the container to be inflated; check valve means at the inlet end of said body, said check valve means being movable between an open position providing for the entrance of ambient atmosphere into said container and a closed position preventing the escape of air from said container; piston means having a passageway arranged for communication with a source of fluid under pressure and terminating in nozzle means projecting into said body at the inlet end thereof; locking means for said check valve means carried by said piston means; and resilient means cooperating with said piston means to hold said locking means in engagement with said check valve means to lock said check valve means in closed position, said fluid under pressure acting on said piston means in opposition to said resilient means to urge said locking means away from said check valve means, to permit said check valve means to open to admit ambient atmosphere.

4. In apparatus for inflating a container, an aspirator comprising a body having inlet and outlet ends, said body being formed for attachment to the container to be inflated; check valve means at the inlet end of said body, said check valve means being movable between an open position providing for the entrance of ambient atmosphere into said container and a closed position preventing the escape of air from said container; locking means including a piston having a passageway arranged for communication with a source of fluid under pressure and terminating in nozzle means inwardly beyond said check valve means; and resilient means cooperating with said piston to urge said locking means into engagement with said check valve means to lock said check valve means in said closed position, said fluid under pressure acting on said piston in opposition to said resilient means to urge said locking means away from said check valve means to permit said check valve means to open to admit ambient atmosphere.

5. In apparatus for inflating a container, an aspirator comprising a body having inlet and outlet ends, said body being formed for attachment to the container to be inflated; a jet nozzle projecting into said body at the inlet end thereof, said nozzle being formed for communication

with a source of fluid under pressure; a plurality of check valves supported adjacent the wall of said body at the inlet end thereof, said check valves being mounted for swinging movement into said body in response to fluid flowing through said nozzle to admit ambient atmosphere; means for limiting outward swinging movement of said check valves to prevent escape of air from said container when said container is inflated; and locking means including a member normally adapted to be urged into engagement with said check valves to hold said check valves in position to prevent escape of air from said container, said fluid under pressure acting on said locking means to move said member away from said check valves to permit said check valves to swing inwardly in said body to admit ambient atmosphere.

6. In apparatus for inflating a container, an aspirator comprising a body having inlet and outlet ends, said body being formed for attachment to the container to be inflated; a jet nozzle projecting into said body at the inlet end thereof, said nozzle being formed for communication with a source of fluid under pressure; a plurality of check

5 valves supported adjacent the wall of said body at the inlet end thereof, said check valves being mounted for swinging movement into said body in response to fluid flowing through said nozzle to admit ambient atmosphere; means for limiting outward swinging movement of said check valves to prevent escape of air from said container when said container is inflated; and locking means including a member normally adapted to be urged into engagement with said check valves to hold said check valves in position to prevent escape of air from said container, said fluid under pressure acting on said locking means to rotate said member out of engagement with said check valves to permit said check valves to swing inwardly in said body to admit ambient atmosphere.
